(57) **CLAIM**

The ornamental design for a light fixture, as shown and described.

DESCRIPTION

FIG. 1 is a bottom perspective view of a first embodiment of a light fixture.

FIG. 2 is a bottom plan view of the light fixture of FIG. 1.

FIG. 3 is a front elevation view of the light fixture of FIG. 1, the rear elevation view being a mirror image of the front view.

FIG. 4 is a right side elevation view of the light fixture of FIG. 1, the left side elevation view being a mirror image of the right side view.

FIG. 5 is a bottom perspective view of a second embodiment of a light fixture, it being understood that the front and rear elevation views of the light fixture are identical to the view

shown in FIG. 3 and that the right and left side elevation views of the light fixture are identical to the view shown in FIG. 4. FIG. 6 is a bottom plan view of the light fixture of FIG. 5. FIG. 7 is a bottom perspective view of a third embodiment of a light fixture.

FIG. 8 is a bottom plan view of the light fixture of FIG. 7. FIG. 9 is a front elevation view of the light fixture of FIG. 7, the rear elevation view being a mirror image of the front view. FIG. 10 is a right side elevation view of the light fixture of FIG. 7, the left side elevation view being a mirror image of the right side view.

FIG. 11 is a bottom perspective view of fourth embodiment of a light fixture, it being understood that the front and rear elevation views of the light fixture are identical to the view shown in FIG. 9 and that the right and left side elevation views of the light fixture are identical to the view shown in FIG. 10. FIG. 12 is a bottom plan view of the light fixture of FIG. 11. FIG. 13 is a bottom perspective view of a fifth embodiment of a light fixture.

FIG. 14 is a bottom plan view of the light fixture of FIG. 13. FIG. 15 is a front elevation view of the light fixture of FIG. 13, the rear elevation view being a mirror image of the front view. FIG. 16 is a right side elevation view of the light fixture of FIG. 13, the left side elevation view being a mirror image of the right side view.

FIG. 17 is a bottom perspective view of a sixth embodiment of a light fixture, it being understood that the front and rear elevation views of the light fixture are identical to the view

shown in FIG. 15 and that the right and left side elevation views of the light fixture are identical to the view shown in FIG. 16.

FIG. 18 is a bottom plan view of the light fixture of FIG. 17. FIG. 19 is a bottom perspective view of a seventh embodiment of a light fixture.

FIG. 20 is a bottom plan view of the light fixture of FIG. 19. FIG. 21 is front elevation view of the light fixture of FIG. 19, the rear elevation view being a mirror image of the front view. FIG. 22 is a right side elevation view of the light fixture of FIG. 19, the left side elevation view being a mirror image of the right side view.

FIG. 23 is a bottom perspective view of an eighth embodiment of a light fixture, it being understood that the front and rear elevation views of the light fixture are identical to the view shown in FIG. 21 and that the right and left side elevation views of the light fixture are identical to the view shown in FIG. 22; and,

FIG. 24 is a bottom plan view of the light fixture of FIG. 23. The break between the two ends of the claimed design shown in broken lines indicates that the design has no specific length. Portions or features of the light fixture not shown in the drawings form no part of the claimed design. The broken lines in the drawings illustrating unclaimed portions of the light fixture and used to indicate no specific length form no part of the claimed design.
